UNITED STATES PATENT OFFICE.

JOHN WOOLRIDGE, OF DEAN'S CORNERS, ASSIGNOR OF TWO-THIRDS HIS
RIGHT TO ABEL B. SMITH, OF CHICAGO, ILLINOIS.

IMPROVEMENT IN ASH-LEACHES.

Specification forming part of Letters Patent No. 150,214, dated April 28, 1874; application filed
March 14, 1874.

To all whom it may concern:

Be it known that I, JOHN WOOLRIDGE, of Dean's Corners, Lake county, Illinois, have invented a new and useful Improvement in Leach-Tubs, of which the following is a full description, reference being had to the accompanying drawings.

Figure 1 is an elevation; Figs. 2 and 3, details.

My invention consists in providing a leach-tub with a receiver, into which the lye from the ashes will pass and be conveyed to a single point, from which it will flow into a suitable receptacle, and in suspending such tub so that it can be emptied by tipping, as described.

In the drawings, A represents a leach-tub, which, for convenience, is quite small at the bottom. B B are suitable posts, to the upper ends of which the tub is pivoted by means of trunnions a. C is a latch, by means of which the tub can be locked in the position shown in Fig. 1 while in use, the lower end of the latch engaging in a notch in b. The tub has a perforated bottom. D is a receiver, concave on the inside, and of such size as to catch all that flows from the tub. At the center, as shown, it is provided with a small tube, e, through which all the lye can pass to a suitable receptacle. If the hole for the escape of the lye from the receiver D be placed in the center, the tube e need not be used, though it will be advisable to use it to prevent the lye from spreading over the under side of D. The receiver D might be provided with a lip at one side to permit and direct the outflow of the

lye. As represented, this receiver D is secured to the tub by means of two hasps, d, and staples e, one on each side of same. f is a hook to prevent the hasp from slipping off from the staple. A hook or pin is used with each hasp and staple. One or both the hasps may be hinged to D.

I do not confine myself to this specific mode of securing the receiver D in place.

The tub can most conveniently be made of staves and circular in form.

The receiver D can best be stamped up from sheet metal, and being removable, when the tub is not in use, it (the receiver D) can be put away in a dry place for preservation.

The tub being suspended on trunnions, it can be tipped over without being removed from the posts, for the purpose of removing the contents when desired.

By the use of this improved leach-tub, waste of lye can be easily prevented, the contents can be emptied with little labor, and considerable annoyance attending the common methods will be avoided.

What I claim as new is as follows:

1. The tub A, in combination with the receiver D, substantially as and for the purposes specified.

2. The combination of the tub A, receiver D, trunnions a, and lock b, substantially as and for the purposes specified.

JOHN WOOLRIDGE.
